United States Patent Office.

OZIAL A. HOWE, OF JERSEY CITY, NEW JERSEY.

Letters Patent No. 82,409, dated September 22, 1868.

IMPROVED MACHINE FOR MAKING HORSE-SHOES.

The Schedule referred to in these Letters Patent and making part of the same.

TO ALL WHOM IT MAY CONCERN:

Be it known that I, OZIAL A. HOWE, of Jersey City, in the county of Hudson, and State of New Jersey, have invented certain new and useful Improvements in Machines for Making Horse-Shoes; and I do hereby declare that the following is a full, clear, and exact description of the same, reference being had to the accompanying drawings, making a portion of this specification, in which—

Figure 1 is a vertical longitudinal section of a machine constructed according to my invention.

Figure 2 is a vertical transverse section of the same, taken in the line $x x$ of fig. 1.

Figure 3 is a detached sectional view of one portion of the same.

Figure 4 is a detached view on a larger scale of one of the horse-shoes made by my machine.

Similar letters of reference indicate corresponding parts in all the figures.

This invention is designed for forming horse-shoes from continuous metal bars, and it consists in so combining a rotating die and presser-disk with each other and an oscillating frame, which carries the die, that the shoe may be bent and shaped upon the end of the bar previous to being severed from the latter.

The invention further consists in a cutting-lip or corner, arranged upon the presser-disk, and in such relation with a suitable shoulder formed upon the die, as to automatically sever the shaped shoe from the bar.

The invention further consists in a presser-cone, provided upon an inclined or oblique shaft, and arranged in such relation with the die and the presser-disk as to effectually retain the metal in proper position with reference to such die and disk, during the operation of shaping the shoe.

The invention further consists in certain novel means of guiding the bar as it is fed inward to the shaping and bending-devices, and also of discharging the shaped shoe from such devices.

To enable others to understand the construction and operation of my invention, I will proceed to describe it with reference to the drawings.

A is the strong base, which supports the other portions of the machine, and which has pivoted longitudinally thereto a frame, B, the journals of which are shown at a . Working longitudinally in the upper part of this frame is a shaft, C, having thereon a spur-wheel, A*, gearing into a similar wheel, B*, upon a shaft, D, arranged above and parallel with the shaft C, and supported in bearings, b , provided on standards, D* D', at the ends of the base, A. Also, provided upon the shaft C are two cams, C* C', extending in opposite directions therefrom, and each working against an anti-friction wheel, E', provided at the adjacent side of the base, A, so that a rotary motion being given to the shaft C from the shaft D by any suitable means, a lateral-oscillating movement will be given to the frame. Secured upon the inner end of the shaft C is a plate, E, upon the face of which is formed the die F, the circumference of which, with the exception of its nearly or quite flat surface, a , corresponds in form to the inner periphery of the shoe, shaped around the same, as hereinafter set forth. Also, formed upon the plate, concentric with and at a slight distance from the just-mentioned circumference of the die, is a rib, b^2 , which extends outward about two-thirds, more or less, of the thickness or circumferential width of the die F, the office of which is to form a continuous recess or depression in the under surface of the shoe, as hereinafter explained.

Attached, upon a suitable pivot at one side of the frame B, in the same plane as the die F, is a roller, c , which may be slightly grooved at its periphery, and below which is the rectangular notch, b^1 , of a bracket, d , also attached to the frame B in such manner that, the stock or iron bar, from which the shoe is to be formed, being passed through the notch b^1 , under the roller c , will be guided in proper position as it passes toward the die.

Situated above the inner bearing of the shaft C is a bearing, d' , supported by suitable standards, a^* , and having passed therethrough a short shaft, e , to the forward end of which, in the same plane as the die F, is a disk, G, and at the opposite end of which is a spur-pinion, f , gearing into a similar pinion, g , on the shaft C, so that the disk G is caused to rotate simultaneously with the die F. The disk is so shaped, that during such movement its circumference will be at a slight but uniform distance from the outer edge of the rib b^2 , except that the corner or lip i upon the disk cuts closely past or upon the part or shoulder, indicated at m , of the die to sever the shoe from the bar, as presently herein set forth.

Working in suitable bearings, provided in the standard D*, is a shaft, I, which receives motion from the shaft D by means of two bevel-pinion, $n\ r$, and is placed at an angle of about forty-five degrees. Formed or provided upon the lower end of this shaft is the presser-cone F*, which is nearly or quite in contact with the surface of the die during the simultaneous rotation of the die, the presser-disk, and the presser-cone, just mentioned.

Attached to the standard D*, contiguous to the presser-cone, is a spring, J, the end of which is bent into a position parallel with the surface of the rib b², as shown at g', and the purpose of which will presently herein appear.

Shown at u , in fig. 3, is a pusher-rod, which works longitudinally in a groove formed in one side of the shaft C , and through a hole formed through the plate E and die F , and which is pressed outward by a spring, V , coiled around the shaft C . The inner end of this pusher-rod is curved outward to form a spur, u , so that at one portion of the revolution of the shaft the spur will strike an inclined plane, u^* , attached to the frame B in such manner that the pusher-rod will be drawn back, the office of the pusher-rod being to throw the shaped or finished shoe from the mould, as hereinafter fully set forth.

In using the machine, the bar of iron from which the horse-shoes are to be made, being first heated to the requisite degree, is thrust endwise through the notch b^1 of the bracket d under the wheel c , and is guided thereby in such manner that its extremity will be pressed against the face of the rib b^2 by the spring g' , and be caught between the corner f' of the presser-disk G and the part or shoulder g^* of the die, and be drawn in between the die and disk, the bar passing in front of the rib b^2 in such manner that the cone F^* may press the same inward upon the rib with its edges forced back to the plate E , simultaneously with which the rotation of the die and disk, by bending the metal around the die and shaping the same by the pressure of the disk thereon, gives the requisite curvature to the shoe and the somewhat tapering form required in the two lateral portions thereof, while the rib b^2 , being indented into the surface of the shoe, forms the channel or recess indicated at a'' , in fig. 4, the inner and outer edges of the under side of the shoe being by this means furnished with rims or flanches, b'' . When the shoe is thus shaped, the lip or corner i of the disk-cutting past, or upon the shoulder m of the die, severs the shoe from the bar. As soon as the shoe is thus severed from the bar, the spring v forces the pusher-rod u outward against the shoe and throws the same from the die, after which, the spur u' of the pusher-rod, striking the inclined plane u^* , the pusher-rod is again drawn inward, whereupon the bar is again pushed or fed inward, and the succeeding shoe is formed in like manner.

What I claim as my invention, and desire to secure by Letters Patent, is—
The combination of the rotating pressure-disk G, the rotating die F, and the oscillating frame B, sub-

1. The combination of the rotating pressure-disk c , substantially as and for the purpose specified.
  2. The cutting-lip or corner i , so arranged upon the presser-disk G , and in relation with the shoulder m of the die F , as to sever the shoe from the bar, substantially as and for the purpose specified.
  3. The arrangement of the rotating presser-cone F^* upon the oblique shaft I , when combined with the presser-disk G and the rotating die F , carried upon the oscillating frame B , substantially as and for the purpose specified.
  4. The arrangement of the guide-notch b^1 and wheel c upon the frame B , and in relation with the rotating die F carried thereby, and the presser-disk G , substantially as and for the purpose specified.
  5. The arrangement of the spring J , with reference to the rotating die F , presser-disk G , and presser-cone F^* , substantially as and for the purpose specified.
  6. The combination of the pusher-rod u , spring v , and inclined plane w^* , with the shaft C and die F , substantially as and for the purpose specified.
